United States Patent Office

Des. 229,169
Patented Nov. 13, 1973

229,169

PACKAGING CUP OR THE LIKE

Franklin W. Weiss, 321 Ardsley Road,
Longmeadow, Mass. 01106

Filed Nov. 17, 1971, Ser. No. 199,835

Term of patent 14 years

Int. Cl. D9—03

U.S. Cl. D9—220

FIG. 1.

FIG. 2.

FIG. 3.

FIG. 4.

FIG. 5.

FIG. 1 is a front elevational view of a packaging cup or the like embodying my new design;

FIG. 2 is a top plan view thereof;

FIG. 3 is a transverse cross-sectional view taken through the packaging cup or the like of FIG. 1;

FIG. 4 is a bottom plan view thereof;

FIG. 5 is an enlarged, fragmentary cross-sectional view taken through the upper left portion of FIG. 1.

I claim:

The ornamental design for a packaging cup or the like, as shown.
